UNITED STATES PATENT OFFICE.

LUDVIG H. NIELSEN, OF WEST LIBERTY, AND JOHN F. BARNARD, OF ALLEGHENY, PENNSYLVANIA, ASSIGNORS TO L. H. NIELSEN CO., OF PITTSBURG, PENNSYLVANIA, A CORPORATION OF PENNSYLVANIA.

DISTRIBUTING-BOARD.

968,071.

Specification of Letters Patent. Patented Aug. 23, 1910.

Application filed October 9, 1907. Serial No. 396,607.

To all whom it may concern:

Be it known that we, LUDVIG H. NIELSEN and JOHN F. BARNARD, citizens of the United States, residing at West Liberty and Allegheny, respectively, in the county of Allegheny and State of Pennsylvania, have invented certain new and useful Improvements in Distributing-Boards, of which the following is a specification, reference being had 10 therein to the accompanying drawing.

Our invention refers to improvements in fuse and switch panels or similar apparatus for making electrical connections and distribution and has for its object to provide 15 a construction which may be permanently installed in a building or elsewhere and used for making the various connections, removals, substitutions, or other changes, without the necessity of removal of any of the surrounding framing or disturbance of the permanent installation. We secure these advantages by means of a base board of any suitable form or design adapted for attachment of the terminal wiring with a removable portion for the circuits, so arranged 20 that by swinging or bodily removing it access may be had to the back, side or ends of the base or bases for any purpose desired. Ordinarily the interior or concealed cavities 25 of apparatus of this character is difficult or impossible of inspection or entrance, and usually requires the removal of the surrounding framing or woodwork, and our invention is designed to obviate these difficulties and provide a simple, convenient, and 30 compact construction of full capacity as to circuits and whereby a continuous face is secured.

In the drawings Figure 1 is a face view of 35 one form of our improved panel. Figs. 2 and 3 are cross sections on the lines II, II, and III, III, respectively.

In the drawings we have shown a double panel board providing a base at each side 40 with a middle movable portion, although it will be understood that the design may be changed to suit local requirements or that the invention may be utilized in various ways to suit the construction, capacity, wiring, circuits, etc.

In the form shown we provide an outer casing 2 of sheet metal, or other suitable material, in box form, having inwardly extending front walls 3, the box or casing being

adapted to be set within a suitable wall cavity and surrounded by any desired finishing, as the panel molding 4 extending over the inner edges of walls 3.

5 is a transverse bracket, two or more of which are preferably provided, secured to the back wall or other portion of casing 2 having terminals 6, 7, located outwardly beyond the back wall of the casing a sufficient distance to provide the desired interior clearance and storage space or capacity and 55 projecting inwardly as shown. Upon these bracket terminals are mounted the panel bases 8, 8, of porcelain, slate, or other suitable non-conducting material, extending lengthwise of the apparatus and secured to 60 the brackets by bolts 9 or other suitable means. At each side edge the bases 8 are preferably provided with outwardly extending edge extensions 10 coinciding at their 65 inner faces with the inner edges of front 70 walls 3 while the ends of the bases 8 are similarly bounded by like extensions, and by this construction it will be seen that the face of the panel board proper is recessed, 75 backwardly beyond the front of the 80 surrounding casing, thereby providing ample clearance for the various fuses, switches, or other attachments or connections. It will be observed also that by this construction an ample cavity 11 is provided 85 between edge extensions 10 and the interior of the casing for wiring, storage, or other purpose.

12 is the switch base, located at one end of the case, extending across underneath the 90 side bases 8 as shown in Fig. 3, mounted on a cross bracket 13 secured to the sides or back of casing 2 to which it is secured in any suitable manner as by bolts or screws 14 which preferably also engage the bases 8, as 95 shown.

15 is the movable portion of the apparatus, consisting in the construction shown, of a metal plate hinged at 16 to the forwardly extending terminals 17 of bracket terminals 100 6, closely adjacent to the inner edge of base 8, extending across and bridging the space between both bases, and lapping over the edge of the base 8 at the opposite side. Said movable portion 15 thus constitutes a swinging front or door, provided with any suitable terminal attaching means at front and back as switches, sockets, binding posts, etc., 105

so arranged that wire connections *a* may be made at the back with the interior terminal connections of the bases 8. If desired, however, the back of the movable element 15 5 may be left plain. When so connected the movable front 15 may be swung out, giving access to the interior for any purpose as stated, and it will be seen that all of the various operations necessary in the installation or use of a panel door of this description 10 may be easily and readily performed by merely opening the front portion 15 as described.

b, b, are the main or trunk line conductors 15 connected by the usual switch *c* with the terminals of a supply circuit, and the fuses *d* establish branch connections through sockets *e* and *f* from conductors *b* to the branch circuits, as shown.

20 The advantages of the invention will be readily appreciated by all those familiar with this class of apparatus. A particular feature of advantage in the movable front is that switches may be mounted on the back of 25 the movable front having their operating parts extending through to the front, thereby preventing all danger of coming into contact with live parts in operating any controlling devices used. It is simple and 30 cheap in construction, readily accessible, may be modified in design or in various ways by the skilled mechanic, and avoids the usual objections attendant on making connections in concealed wiring.

35 What we claim is—

1. A distributing board provided with a permanent base at each side having terminal attaching devices, and an intervening space, a movable portion mounted upon one 40 of said bases arranged to close or open said space and having terminal attaching devices for flexible connection with the permanent attaching devices of each base, and a surrounding casing inclosing said parts, substantially as set forth.

2. A distributing board provided with a permanent base at each side having terminal attaching devices, and an intervening space, a movable portion mounted upon one 50 of said bases arranged to close or open said space and having terminal attaching devices for flexible connection with the permanent attaching devices of each base, trunk line conductors connected with the terminal 55 attaching devices of the permanent bases, and means for establishing circuit connections therewith located between the permanent bases, substantially as set forth.

3. In a distributing board, the combina-

tion of a casing provided with supporting 60 brackets, a permanent base secured on said brackets, and a movable portion hinged on said brackets and provided with attaching devices for wiring with the base, substantially as set forth.

4. In a distributing board, the combination of a casing provided with supporting 70 brackets, permanent bases secured within the casing on said brackets, and a movable portion hinged on said brackets and provided with attaching devices for wiring with the base, substantially as set forth.

5. In a distributing board, the combination of a casing provided with supporting 75 brackets, permanent circuit bases provided with fixed terminal fuse devices and a main switch base secured to said brackets, and a middle movable portion hinged to said brackets at one side and provided with attaching devices for wiring with the circuit 80 bases, substantially as set forth.

6. In a distributing board, the combination of a casing provided with outwardly spaced inwardly extending front walls, supporting brackets mounted within the casing, permanent circuit bases secured within the casing on said brackets provided with fixed 85 terminal fuse devices, outwardly extending terminal walls therefor coinciding with the front walls, and a movable portion hinged to said brackets at one side and provided with attaching devices for wiring with the circuit bases, substantially as set forth.

7. In a distributing board, the combination with a casing provided with supporting 95 brackets and a permanent base secured on said brackets provided with a main conductor and fixed laterally arranged attaching devices, of a relatively movable portion provided with attaching devices for flexibly 100 wiring with the attaching devices of the base, substantially as set forth.

8. In a distributing board, the combination with a casing provided with supporting 105 brackets and permanent bases secured on said brackets each provided with a main conductor and fixed laterally arranged attaching devices, of a relatively movable portion provided with attaching devices for flexibly 110 wiring with the attaching devices of the bases, substantially as set forth.

In testimony whereof we affix our signatures in presence of two witnesses.

LUDVIG H. NIELSEN.
JOHN F. BARNARD.
